COMBINED BATTERY HOLDER AND CAPACITOR FOR PHOTOGRAPHIC FLASHLIGHTS OR SIMILAR ARTICLES

John W. Kinney, Jr., Cincinnati, Ohio, and Marl McMath, Newport, Ky., assignors to J. Warren Kinney, Jr., Cincinnati, Ohio

Application August 9, 1950, Serial No. 11,674

Term of patent 14 years

(Cl. D48—24)

To all whom it may concern:

Be it known that we, John W. Kinney, Jr., and Marl McMath, citizens of the United States, residing at Cincinnati, county of Hamilton and State of Ohio, and Newport, county of Campbell and State of Kentucky, have invented a new, original, and ornamental Design for a Combined Battery Holder and Capacitor for Photographic Flashlights or Similar Articles, of which the following is a specification, reference being had to the accompanying drawings, forming part thereof.

Fig. 1 is a front elevational view of a combined battery holder and capacitor for photographic flashlights or similar articles, showing our new design.

Fig. 2 is a side elevational view thereof.

Fig. 3 is a bottom plan view of the device of Fig. 1.

Fig. 4 is a top plan view of the device.

We claim:

The ornamental design for a combined battery holder and capacitor for photographic flashlights or similar articles, as shown.

JOHN W. KINNEY, JR.
